UNITED STATES PATENT OFFICE

138,708

DESIGN FOR AN INFANT'S SHOE OR SIMILAR ARTICLE

John M. Galber, Lynn, Mass.

Application July 15, 1944, Serial No. 114,408

Term of patent 14 years

(Cl. D7—7)

To all whom it may concern:

Be it known that I, John M. Galber, a citizen of the United States of America, residing at Lynn, in the county of Essex and Commonwealth of Massachusetts, have invented a new, original, and ornamental Design for an Infant's Shoe or Similar Article, of which the following is a specification, reference being had to the accompanying drawing forming a part thereof.

Fig. 1 is a plan view of an infant's shoe showing my new design;

Fig. 2 is a side elevation of the shoe;

Fig. 3 is a front elevation of the shoe; and

Fig. 4 is a rear end elevation of the shoe.

I claim:

The ornamental design for an infant's shoe or similar article, substantially as shown.

JOHN M. GALBER.
